Philip Sawyer Rice (Hand)

UNITED STATES PATENT OFFICE.

OTTO L. RAABE, OF JERSEY CITY, NEW JERSEY, ASSIGNOR TO R. HOE AND CO., OF NEW YORK, N. Y., A CORPORATION OF NEW YORK.

IMPRESSION-ADJUSTING AND BLANKET-IRONING DEVICE.

1,396,056.

Specification of Letters Patent.

Patented Nov. 8, 1921.

Original application filed January 22, 1917, Serial No. 143,584. Divided and this application filed January 2, 1920. Serial No. 349,009.

To all whom it may concern:

Be it known that I, OTTO L. RAABE, a citizen of the United States, residing at Jersey City, county of Hudson, and State 5 of New Jersey, have invented certain new and useful Improvements in Impression-Adjusting and Blanket-Ironing Devices, fully described and represented in the following specification and the accompanying drawings, forming a part of the same.

This invention relates to certain improvements in printing machines, and this application is a division of my co-pending application Serial No. 143,584, filed January 22, 15 1917.

Certain classes of printing machines, particularly the fast rotary web machines, are run during the printing operation at very high speed. The cylinders of these machines are heavy and the high speed at which modern printing conditions require them to be run causes a "throwing" or jumping which produces a bad impression and heavy strain and considerable wear on the press, 20 this being particularly so in machines employing long cylinders of say six or more pages wide.

In this class of machines the impression cylinder is provided with a blanket of some 30 comparatively resilient material to effect a good impression. After these blankets have been in use for some time, particularly where the printing is done from plates arranged in the same position on the form cylinder, the spaces between the plates or margin spaces, cause bolsters or ridges in the blanket and these ridges are liable to cause breakage of the web at such points, and also are liable to produce a bad impression.

It is the object of the present invention to produce an improved construction for supporting the impression cylinder so as to prevent this "throwing" or jumping when the cylinder is running at high printing 45 speed and by which the impression cylinder may be adjusted to vary the impression, this construction being such that it will not obstruct convenient access to the running parts of the press.

It is a further object of the invention to produce a construction which will iron or

smooth out the blanket on the impression cylinder so as to avoid the objectionable bolsters or ridges and keep the blanket of a smooth and even surface throughout.

55

The invention consists in constructions for effecting this and other objects not specifically referred to, such constructions including novel parts and arrangements shown in the accompanying drawing in which:

60

Figure 1 is a side elevation, partly broken away of so much of a rotary printing machine with the invention embodied therein as is necessary for an understanding thereof.

65

Fig. 2 is an enlarged detail partly broken and partly sectional view of the impression cylinder support and adjusting means, and

Fig. 3 is a broken, partially sectional side view of the construction illustrated in Fig. 2.

70

Referring now to the drawings, the invention has been illustrated as embodied in a rotary printing machine in which the printing members are cylinders, and in which but one printing couple has been illustrated; but it will be understood that the invention may 75 be employed for as many couples as there are in the machine, the construction being duplicated for the impression cylinders of each couple.

As shown, the moving parts of the machine are supported in frames 1 of any suitable construction. The printing mechanism shown is a rotary couple including a form cylinder 2 and an impression cylinder 3. The form and impression cylinders are pref- 85 erably for economy in space and convenience in arrangement, arranged vertically of each other with the impression cylinder below, this arrangement having certain advantages. The form cylinder may be inked in any 90 usual manner, but, as shown, is inked through a pair of distributing rolls 4 receiving ink from a distributing cylinder 5 which is supplied with ink from a fountain 95 6 through a fountain roll 7, distributing ductor rolls 8, 9, and a transfer roll 10 located between the two ductor rolls. Ma- 100 chines embodying the invention will include mechanism for supporting the impression cylinders, and for adjusting the impression.

Where the impression cylinder is a blanketed cylinder means for ironing or smoothing out

and keeping smooth the surface of the blanket will be provided, and in machines embodying the invention in its best form, a single means will be employed for effecting 5 both the supporting, adjusting and ironing functions. While the particular mechanism employed may be varied, a simple supporting, adjusting and ironing mechanism is that shown, in which there is provided in 10 the side frames 1 on each side of the machine, a block or base 11. In these blocks are supported a pair of rolls 12 and 13, so that they may be given a vertical adjustment to and from the impression cylinder whereby 15 the cylinder may be adjusted to and from its coöperating form cylinder to vary the impressions. These rolls are, as shown, spaced from each other and contact with the surface of the cylinder at points on opposite sides of the vertical axis and extend substantially the length of the cylinder forming in effect a cradle in which the cylinder rests, the rolls thus effecting a support for the cylinder. 20

25 These rolls may be mounted in various ways so as to have this vertical adjustment, but preferably are so mounted that they may be moved simultaneously an equal amount so as to get an even supporting and adjusting movement for the impression cylinder. 30 As illustrated, these rolls are mounted on shafts 14, 15, each of which has at each end a reduced end 16 which takes bearing in an eccentric rotatable sleeve 17 eccentrically 35 mounted in bearing blocks 18 secured to the base blocks 11 by means of bolts 19, or in any other manner, the rolls being free running in the sleeves. Each of the sleeves is formed with a gear 20, and these gears are operated 40 through actuator gears 21, 22, in mesh with each other, one of these actuator gears, as 22, being carried on a shaft 23 having squared ends 24 projecting beyond the blocks 11, through which it may be operated 45 by a hand crank from either side of the machine. By operating the gear 22 the gears 17 on each of the rolls 12, 13 are equally rotated and the center of each of the rolls consequently simultaneously and equally 50 moved, causing a like movement of the impression cylinder and evenly adjusting the impression as desired, and furthermore, this adjustment may be effected while the machine is in operation. The rolls are thus 55 kept in close contact with the cylinder and this results in preventing sagging and consequent "throw" or jumping of the cylinder when running at high printing speed. The gears are prevented from rotating after ad- 60 justment in any suitable manner, as by a latch 26 pivoted on one of the bearing blocks 18.

When the impression cylinder is a blanketed cylinder as shown in the present embodiment of the invention, the blanket being in-

dicated by the numeral 25, these rolls 12, 13 are preferably made of hard metal so that they will act as ironing or smoothing rolls to smooth or iron out the blanket on the cylinder and prevent formation of bolsters or ridges caused by the plate margins. These rolls, therefore, effect the functions of supporting and adjusting the impression cylinder and of ironing out the blanket of such cylinder where a blanket is employed. 75

While these impression, adjusting and ironing rolls may, of course, be omitted from any couple, it will be understood that in the machine embodying the invention in its best form, such rolls will be provided for the impression cylinder of each printing couple, the construction and operation of the rolls in each case being the same. 80

While a simple and convenient construction for effecting the purpose of the invention has been illustrated and described, it will be understood that various changes may be made in the type of rolls employed and in the means for operating the rolls to effect their various functions, and that the invention is not restricted to the arrangement shown. 85

What I claim is:

1. In a printing machine, the combination with a form and impression cylinder arranged vertically with the impression cylinder below, of a pair of rolls located below the cylinder and on opposite sides of its vertical axis and on which the cylinder rests, and means for adjusting the rolls to vary the impression. 95

2. In a printing machine, the combination with a form and impression cylinder arranged vertically with the impression cylinder below, of a pair of rolls located below the cylinder on which the cylinder rests, eccentric bearings for the rolls, and means for simultaneously rotating the bearings for adjusting the rolls to vary the impression. 105

3. In a printing machine, the combination of an impression cylinder, of a support for the cylinder located below the horizontal axis thereof on which the cylinder surface rests, and means for operating the support while the cylinder is in contact therewith for adjusting the impression. 110

4. In a printing machine, the combination of an impression cylinder, of supports located below the horizontal axis of the cylinder and on each side of the vertical axis and on which the cylinder rests, and means for moving the supports to adjust the impression while the cylinder is in contact therewith. 120

5. In a printing machine, the combination with an impression cylinder, of a pair of eccentrically mounted rolls located below the cylinder on which the cylinder rests, gears on the rolls, an actuator, and means for operating the actuator for simultaneously rotat- 125 130

ing the gears for adjusting the rolls against the cylinder.

6. In a printing machine, the combination with a form and impression cylinder arranged vertically with the impression cylinder below, of a pair of rolls located below the cylinder on which the cylinder rests, eccentric bearings for the rolls, gears carried on each of the rolls, an actuator coöperating with the gears, and means for operating the actuator for simultaneously rotating the gears for adjusting the rolls against the cylinder.

7. In a printing machine, the combination with a printing couple including a form and impression cylinder arranged vertically with the impression cylinder below, of a blanket on the impression cylinder, a pair of hard metal ironing rolls below and contacting 20 with the blanket and extending substantially the length thereof for ironing out the

blanket, and means for vertically adjusting the rolls against the cylinder.

8. In a printing machine, the combination of an impression cylinder, a blanket thereon, 25 and a hard metal ironing roll extending substantially the length of the cylinder below the same and in pressure contact with the blanket for ironing out the blanket throughout its length, and means for adjusting the 30 roll to vary the impression.

9. In a printing machine, the combination of an impression cylinder having a blanket thereon, and a common means acting to adjustably support the impression cylinder 35 throughout its length for varying the impression and to iron out the blanket throughout its length.

In testimony whereof, I have hereunto set my hand.

OTTO L. RAABE.
